APPARATUS FOR MIXING GASEOUS FLUIDS

Filed April 22, 1927 2 Sheets-Sheet 2

FIG. 2.

UNITED STATES PATENT OFFICE

CHARLES PRACTHE, OF PARIS, FRANCE

APPARATUS FOR MIXING GASEOUS FLUIDS

Application filed April 22, 1927, Serial No. 185,872, and in France March 29, 1927.

My invention relates to improvements in apparatus for mixing gaseous fluids of the injector-compressor type, in which a gaseous fluid for driving an engine for example, is mixed with and carries along a second gaseous fluid.

My invention is comprised in certain novel forms, constructions, and combination of parts, the objects of which are to provide a reliable apparatus for the purpose stated, all of which will hereinafter be fully described and claimed.

Before proceeding with a detailed description of my apparatus it is well to briefly refer to the prior art in order to better understand the specific objects of my invention. Numerous types of apparatus are known in the art which are designed to produce a sucking in and compression of a gas or vapor by means of the kinetic energy of a jet of gas expanding in an appropriate recess. Such apparatus usually comprises essentially a converging-diverging passageway having a contracted section of elongated rectangular form of small cross-section which opens into a diverging pipe pierced with openings designed to permit the gas to be mixed to be drawn in.

In apparatus of this character the gaseous engine fluid passes through the recess in the form of a very thin gaseous stream of great length and taking the shape of a dihedral angle. This gaseous stream in penetrating a diverging expansion pipe attains great suction power and permits the gaseous fluid to be mixed and carried along to be drawn in through orifices in said expansion pipe with a force proportional to the distance between said contracted section of the passageway and said orifices. The kinetic energy of the mixture thus formed is then transformed into pressure in a chamber formed by a prolongation of the mixing or expansion pipe.

It is well recognized that in apparatus of this character, that the particles of the gaseous motor fluid can only expand in a single direction, that is, in planes perpendicular to the apex of the dihedral angle formed by the intersection of the two streams of fluid. That such a condition in the operation of the apparatus is undesirable is manifest.

It will be noticed that the useful effect of apparatus of this character is directly influenced by the number of particles in the jet of gaseous motor fluid in the zone of its periphery and consequently capable of coming into immediate contact with the gaseous fluid to be mixed therewith and carried along. The larger the periphery of the contracted section of the passageway is made the greater the number of particles capable of coming into contact with the gaseous fluid to be mixed will be and hence the greater will be the useful effect of the apparatus.

It is the object of this invention to subdivide the contracted section into a series of circular sections of a diameter equal to the width of the rectangular contracted section and to arrange a plurality of mixing pipes to be fed by a common feed pipe and to discharge through an appropriate diffuser into a common collector pipe.

Other objects of the invention will be obvious to those skilled in the art to which my invention appertains in the following specification when taken in connection with the accompanying drawing, in which—

Fig. 1 is a longitudinal sectional view through the apparatus forming my invention.

Fig. 2 is an end elevational view of the apparatus shown in Fig. 1, parts being in section.

Referring to the drawings, numeral 1 represents a conduit which conducts the gaseous fluid to be mixed to the converging-diverging expansion pipe 2 and in which the contracted section is shown at 3 and the diverging section at 4.

This expansion pipe is fixed to a plate 5 to which is also fastened the wall 6 of the conduit 1.

Integral with the diverging section 4 of expansion pipe 2 is a mixing pipe 7, on the periphery of which are disposed a plurality of orifices 8 which are symmetrically disposed in a plurality of circles successively placed on the conical surface of said pipe.

The orifices 8 are circular in form and are inclined to the extent desired with respect to the axis of the expansion pipe 2. These ori-

fices may be formed by superposing a plurality of circular rings 9 in the form of a truncated cone or in any other suitable manner.

The mixing pipe 7 is prolonged to form the conical section 10 which acts as a so-called diffuser in which the mixture before leaving gradually loses its velocity and acquires pressure.

A number of mixing elements 11 of this character are arranged in groups with the enlarged ends of the pipe sections 10 attached to the four faces of a distributing pipe 12 and communicating therewith, the distributing pipe 12 having the form of a parallelepiped of square cross-section. Said distributing pipe is closed at its lower extremity and carries a circular section 13 at its upper extremity.

Each group of mixing tubes is fastened to the pipe 12 by means of the large conical base of the mixing element. Each of the four groups of mixing elements thus formed is enclosed by a casing 14 in the form of a parallelepiped and whose walls extend to those of the square distributing pipe 12. The four casings when assembled form a cross of which the pipe 12 is the center. The exterior walls 15 of said casings carry the small ends of the mixing elements 11 and into which said mixing elements open, as shown at 16.

A pipe 17 opens into each of the casings through wall 15 and serves to conduct the gaseous motor fluid to the mixing elements 11. The four pipes 17 are interconnected by a feed pipe of circular form 18 which receives the motor fluid through an inlet pipe 19. Each casing 14 is closed at its lower end by means of a cover 20 and the upper ends are closed by a wall 21. Couplings 22 are provided on walls 21 which connect the casings 14 with a circular distributing pipe 23 which receives the gaseous fluid to be mixed with the motor fluid through an inlet pipe 24.

The operation of my apparatus is as follows:

The gaseous main or motor fluid is brought to the feed pipe 18 through the inlet pipe 19 and feeds each group of mixing elements through the pipes 17.

The gaseous fluid to be mixed and carried along in the main fluid is brought in through the inlet pipe 24 and by means of the distributing pipe 23 and couplings 22 is fed to each of the casings 14 and hence to the orifices in the mixing elements.

The compressed mixture given off by each diffuser of the mixing tubes is collected in the central pipe 12 and led off through the pipe 13.

Having thus described my invention what I claim as new and desire to secure by Letters Patent is—

1. In a device for mixing gaseous fluids of the type described, a central discharge conduit, a plurality of groups of Venturi tubes

radiating from said conduit and each having one end opening into said conduit, means common to said Venturi tubes for supplying a gaseous fluid to said tubes, additional means common to said tubes for supplying a second gaseous fluid to said tubes and means for causing a flow of said first named gaseous fluid through said tubes to entrain and produce a flow of said second gaseous fluid.

2. In a device for mixing gaseous fluids of the type described, a central discharge conduit, a plurality of groups of Venturi mixing tubes radiating from said conduit and each having one end remote from the restricted portion of said Venturi opening into said conduit, a supply pipe into which the other end of said mixing tubes open, said supply pipe being common to said groups of mixing tubes, means for supplying said supply pipe with a gaseous fluid, a casing surrounding said mixing tubes, means for supplying said casing with a second gaseous fluid and means in said mixing tubes for causing the introduction of said second fluid into said tubes when said first fluid passes therethrough.

3. In a device for mixing gaseous fluids of the type described, a central discharge conduit, a plurality of Venturi mixing tubes radiating from and opening into said conduit, means common to said mixing tubes for supplying a gaseous fluid to said mixing tubes, and means communicating with said Venturi tubes adjacent the restricted portions thereof for supplying a second gaseous fluid to said tubes, said fluid supplying means cooperating to cause one of the fluids to be drawn in by the other through its kinetic energy and for subsequently transforming said kinetic energy into pressure when the fluids become mixed.

4. In a device for mixing gaseous fluids of the type described, a central discharge conduit, a plurality of groups of Venturi mixing tubes radiating from and each having one end opening into said conduit, a supply pipe into which the other ends of each of said groups of said mixing tubes open, each of said supply pipe being common to one of said groups of mixing tubes, means for supplying said supply pipes with a gaseous fluid, a casing surrounding each group of said mixing tubes, means for supplying said casing with a second gaseous fluid and means in said mixing tubes for causing one of the fluids to be drawn in by the other through its kinetic energy and for subsequently transforming said kinetic energy into pressure when the fluids become mixed.

5. In a device for mixing gaseous fluids of the type described, a square discharge conduit, a plurality of groups of mixing devices for said conduit, there being one group opening into each face of said conduit, each mixing device comprising a cone-shaped tube, a

converging-diverging orifice at the small end of said tubes for giving a gaseous fluid passing therethrough a relatively high velocity, openings in said tubes inclined with respect to the longitudinal axes of the tubes disposed adjacent the diverging portions of said orifices, the walls of said tubes extending in the same direction as the diverging portions of said orifices and making the same angle 5 with the longitudinal axes of said tubes whereby the velocity of a gaseous fluid passing through said orifices is diminished and its kinetic energy transformed into pressure means common to said mixing devices for 10 supplying a gaseous fluid to said mixing devices through the said converging-diverging orifice and means common to the openings in said tubes for supplying gaseous fluid to said mixing devices through said openings.

20 6. In a device of the type described, a centrally disposed discharge pipe, a group of mixing pipes radiating from said discharge pipe and communicating therewith, an annular supply pipe communicating with the other 25 ends of said mixing pipes, a plurality of casings for said mixing pipes there being one fluid-tight casing for each group of mixing pipes, said casings communicating with the interior of the mixing pipes enclosed thereby, a second annular supply pipe disposed on the upper wall of said casings, a coupling interconnecting each of said casings with 30 said second annular supply pipe and an inlet for said second supply pipe.

35 7. In a device of the type described, a centrally disposed square discharge pipe, a group of mixing pipes extending from each surface of said discharge pipe, an annular supply pipe communicating with the other ends of 40 said mixing pipes, a plurality of casings for said mixing pipes there being one fluid-tight casing for each group of mixing pipes, a second annular supply pipe disposed on the upper wall of said casings, a coupling 45 interconnecting each of said casings with said second annular supply pipe, an inlet for said second supply pipe and means in said mixing pipes for causing one of the gaseous fluids supplied to apparatus to draw in a 50 second gaseous fluid supplied to the apparatus by its kinetic energy and for subsequently transforming said kinetic energy into pressure when the fluids become mixed.

55 8. In a device of the type described, a centrally disposed discharge pipe, a group of mixing pipes extending from each surface of said discharge pipe, an annular supply pipe communicating with the other ends of 60 said mixing pipes, each of said mixing pipes comprising a cone-shaped tube, a converging-diverging orifice at the small ends of said tubes for giving a gaseous fluid passing therethrough a relatively high velocity, openings 65 in said tube inclined with respect to the longitudinal axes of the tubes disposed adjacent

the diverging portions of said orifices the walls of said tubes extending in the same direction as the diverging portions of said orifices and making the same angles with the longitudinal axes of said orifices whereby the 70 velocity of a gaseous fluid passing through said tubes is diminished and its kinetic energy transformed into pressure, a plurality of casings for said mixing pipes there being one fluid-tight casing for each group of mixing pipes communicating with the pipes therein by means of said openings, a second annular supply pipe disposed on the upper 75 wall of said casings and a coupling interconnecting each of said casings with said second annular supply pipe.

In testimony whereof I have affixed my signature.
